UNITED STATES PATENT OFFICE.

FRANK N. REEVES, OF NEWARK, NEW JERSEY, AND ALBEN E. LUNDELL, OF NEW YORK, N. Y., ASSIGNORS TO WESTERN ELECTRIC COMPANY, OF NEW YORK, N. Y., A CORPORATION OF ILLINOIS.

AUTOMATIC TELEPHONE-EXCHANGE SYSTEM.

1,115,739.

Specification of Letters Patent.

Patented Nov. 3, 1914.

Application filed May 10, 1913. Serial No. 766,904.

To all whom it may concern:

Be it known that we, FRANK N. REEVES and ALBEN E. LUNDELL, citizens of the United States, residing at Newark, in the 5 county of Essex and State of New Jersey, and at New York, in the county and State of New York, respectively, have invented a certain new and useful Improvement in an Automatic Telephone-Exchange System, of 10 which the following is a full, clear, concise, and exact description.

This invention relates to an automatic switching system and particularly to a telephone exchange system comprising one 15 or more main offices and one or more sub-offices or satellites associated and connected therewith by trunk lines. In a multi-office satellite system there would be provided trunk lines leading from each 20 main office to each other main office of the system, and other trunk lines leading from each main office to its own satellites. Such a system may have, for example, 10 main offices, each with its satellites having 25 a capacity of 10,000 lines, making a total capacity of 100,000 lines. The capacity of the satellites may be for instance, 1000 subscribers' lines each, although obviously the number may vary according to the requirements met with in practice. The subscribers' lines may terminate either in a satellite or in a main exchange.

The object of this invention is to economize in the use of trunk lines between the 35 satellites and the main exchange offices without the necessity of variable manipulation of the subscribers' calling devices to discriminate between calls local to the satellite and calls requiring connection through a 40 main office. To this end automatic discriminating means are provided which operate without the necessity of any knowledge on the part of the operator manipulating the calling device, whether the wanted 45 subscriber is connected to the same satellite as the calling subscriber or to a main office or some other satellite of the exchange, the calling device being manipulated in the same manner for all connections described, and 50 strictly in accordance with the substation numbers of the subscribers wanted.

The characteristic feature of this invention is that it provides in an automatic exchange system, means whereby a plurality of

switch mechanisms, each having access to a 55 different group of lines, are simultaneously actuated by the first series of impulses from a controlling device and whereby, upon the succeeding series of impulses, the circuit is extended through only that one of said 60 switches which has access to the line of the called subscriber.

The invention will be more readily understood by reference to the accompanying drawings wherein—

Figure 1 is a diagrammatic illustration of the multi-office satellite system embodied in the invention, and Figs. 2 and 3 when placed together with Fig. 3 to the right of Fig. 2, represent the circuits and apparatus involved in establishing the connection between subscribers at the same satellite. Fig. 2 represents a subscriber's station and line switch and the "repeater" and register selector associated therewith. Fig. 3 represents a hundreds selector and a connector at the satellite and a called subscriber's line and substation apparatus.

In Fig. 1 of the drawing, E represents a main office connected by trunk lines 100 to 80 other main offices A, B, C, D and F, it being understood that similar trunk lines would extend from each main office to each of the other main offices of the exchange. Associated with the main office E, the confines of 85 which are indicated by the dotted rectangle, are the satellites E¹, E² and the subscribers' stations e¹ e² which are located at the satellite E² and other subscribers' stations d³ d⁴ connected directly with the main office. 90 Similarly associated with the main exchanges A, B, C, D and F are satellites A¹, A², A³, B¹ B² B³, C¹, C², C³, D¹, D², D³, F¹, F², F³, respectively, and subscribers' stations a¹, a², b¹, b², etc., the satellites being 95 represented by the circles and the subscribers' stations by the small squares. The main office E may include a number of series of switching mechanisms represented therein as a first selector 101 and second selector 102, third selector 103 and final selector or connector 104. Trunk lines would preferably extend from the second selectors 102 to third selectors at each of the other main exchanges, as well as to the third selector 105 103 at the same exchange therewith. In addition to the third selectors to which the trunks from the second selectors extend,

other third selectors would be provided for the trunks extending from the second selectors of other exchanges.

The apparatus at a satellite office E^1 for instance, may include trunk finders 105, repeaters 106, register selectors 107, hundreds selectors 108 and final connectors 109 and 110. The arrangement of the apparatus thus illustrated in Fig. 1 is such that the subscriber at station e^1 for example, may complete a talking circuit to the subscriber's station e^2 over a local connecting circuit as 111 which is wholly within the satellite, or he may complete a connection to any other subscriber of the exchange system whose line does not terminate at the satellite E^1 over a trunk line such as 112 leading to the main office E from whence the connection may be extended in the usual manner according to the particular location of the wanted subscriber. If any subscriber other than those connected to the satellite E^1 desires a connection with the subscriber at this satellite, the circuit would be completed by way of selectors 101, 102, 103 variously positioned at the main exchanges according to the location of the calling subscriber, and through a trunk line as 113 to a final connector as 110 at the satellite E^1 through which the subscribers thereat would be reached when the call originated at any point in the exchange other than at the satellite E^1 . The manner in which certain of these connections are accomplished will be hereafter described in detail. At this point it is sufficient to say that when the subscriber at e^1 removes his receiver from the hook, the trunk finder 105 will pick a pair of connecting circuits as 111 and 112 of which 111 leads to the connecting apparatus individual to the satellite, while 112 leads to a first selector 101 at the main exchange E . If now the subscriber at e^1 sends calling impulses in correspondence to the number of some other station at the same satellite therewith, the brushes of the register selector 107 (the construction of which is similar to a final connector) will first be stepped up to the level corresponding to the number of tens thousand impulses in response to the first series, and would then be rotated step-by-step in response to the thousand series of impulses until the brushes thereof rest on the terminals representing the thousand at the satellite. Simultaneously with the actuation of the register selector, the brushes of a first selector 101 at the main exchange E will be stepped up to a corresponding level, and after having picked an idle second selector 102, the brushes of this second selector will be stepped up in unison with the rotary step-by-step movement of the brushes of the register selector. If as assumed the brushes of the register selector now rest on contacts

representing the thousand of the satellite, a circuit for a cut-off relay will be completed which will operate to interrupt the connecting circuit 112, and the selectors 101 and 102 will then obviously return to normal. The succeeding series of impulses will now act in the usual manner to cause the hundreds selector 108 to pick an idle final connector 109 having access to the desired subscriber's line, and will then direct the brushes of this final connector to the terminals of this line.

Referring now to Figs. 2 and 3 wherein the circuits and apparatus required for the establishment of a connection between subscribers at e^1 and e^2 are illustrated, each subscriber's line such as 200, 201, is provided at the substation with the usual telephone apparatus and with a calling device or interrupter 202, the purpose of which is to produce the operating impulses by interrupting the circuit at the substation, and at the satellite exchange with a trunk finder 105. The side 200 of the line leads to switch spring 203, also to the back contact 204 of armature 205 of the electromagnet 206. The side 201 of the line extends to the switch spring 207, also to the contact 208 of armature 209. In addition to these branches from the sides 200 and 201 of the line, additional branches are provided to multiple terminals 210 and 211 of the connectors through which the subscriber at e^1 may be reached when called.

The trunk finders may comprise any suitable mechanism, that shown being similar to the switch shown in the British Patent No. 26,301 of 1906. The plunger 212 of this switch, as is well understood, always stands before the set of springs associated with an idle connecting circuit, and upon sufficient energization of the electromagnet 206, this plunger will be drawn forward, forcing the insulating ball 213 thereof between the innermost springs of the set, whereby each of the four springs of the set is forced outwardly into engagement with its co-operating contact. The lead 214 associated through contact 215 with grounded switch spring 216 leads through the armature 250 and back contact to a master switch such as shown in the beforementioned British patent, whereby through the actuation of well known means, all of the remaining idle plungers of the group are moved to a position before the springs associated with the next idle trunk. Current is supplied to the lead 217 through the normally closed contact 218, but during the interval when the switch plungers are in transit from one position of rest to the next, this circuit is opened at contact 218 so that no finder mechanism can be actuated during this interval.

As hereinbefore stated, when a call is local to the satellite the calling subscriber's

line will be extended by the register selector 107, the hundreds selector 108 and the connector 109 to the terminals of the called subscriber's line. The apparatus of the register selector may be substantially that of a connector, the circuits, however, being varied in order that it may fulfil its function in this invention. The hundreds selector and the connector may comprise apparatus such as is well known in the art and need not be fully described here. A selector and connector similar to that shown in the above noted British patent, and more specifically described in United States Patents Nos. 815,321 and 815,176, respectively, would be satisfactory. The selector may be of the two-movement type wherein a series of steps is taken to select the desired hundreds group of connectors, and which then automatically hunts for an idle connector of that group. The connector may also be of the two-movement type in which the brushes are first stepped to a certain group of tens contacts and are then moved to the terminals of the called subscriber's line.

In Fig. 3 is shown the talking circuit conductor of the apparatus including contacts 400 and 401 of the hundreds selector 108, and 402 and 403 of the connector 109, also condensers 404 and 405, impedance coil relays 406, 407 connected in bridge of the talking circuit on each side of the condensers and through which talking current is supplied to the calling and called subscribers from battery 408. Associated with the selector and connector switches 108 and 109 there would preferably be local test and holding contacts 409 and 410 respectively. The brush of the latter is adapted to be connected to ground at 411 when the connector is brought to rest on the terminals of a called line, the object of this being to create a busy test condition at the multiple terminals of the called subscriber's line. It will, of course, be understood that the line of the called subscriber will have associated with it trunk finders such as shown in association with the line of the calling subscriber e^1 , and that the connections to such apparatus will be made by the conductors 412 and 413.

As a further description of the apparatus employed is not believed to be necessary, the operation of the system will now be described: Let it be assumed that the subscriber at station e^1 is calling the subscriber at e^2 , these two stations being connected to the same satellite, and let it be further assumed that this satellite contains a group of subscribers' lines from 99,000 to 99,999 and that the number of the called subscriber is 99,532. The calling subscriber at station e^1 removes his receiver from the hook, thereby closing the line circuit through the winding

219 of the electromagnet 206, the current 65 flowing from the live side of grounded battery 220 through 219, armature 209, contact 208, side 201 of the line, substation apparatus, side 200, contact 204, and armature 205 to ground. This partially energizes the 70 electromagnet 206 and the armature 221 alone is attracted. The attraction of this armature closes a circuit from grounded battery through the normally closed contact 218, lead 217, windings 222 and 223 of electromagnet 206, contact and armature 221 to ground. This results in the attraction of the left armatures 209 and 205 and of the right armature 224. The armature 224 actuates the plunger 212 to force the insulating knob 213 between the innermost contact springs, thus closing all the springs now associated with this plunger to their contacts. The armature 224 in pulling up engaged the contact 225, closing a short circuit about 80 the winding 222 whereby the electromagnet 206 is made slow to release. It may be noted that the energizing circuit through the winding 223 will be interrupted at the 85 contact 218 upon the grounding of the contact 215 by the switch spring 216 as this places ground on the lead 214 to the master bank, thus causing the idle plungers to move to a position before the next idle trunk. However, as the electromagnet 206 is made 90 slow to release by the short circuiting of the winding 222, all of its armatures will be held up until a holding circuit is completed 95 through the coil 226.

When the plunger entered the set of 100 springs, the sides of the subscriber's line were extended by springs 203 and 207 and a circuit was completed as follows: from live pole of grounded battery 251, left winding of relay 252 at the repeater, contact 253, 105 armature 254, contact and spring 207, side 201 of the line, substation apparatus, side 200 of the line, switch spring 203 and contact, conductor 227, winding of relay 275 of the register selector, contact 276, side switch 110 wiper 277, conductor 278, armature 255 and back contact and right winding of relay 252 to ground. This causes the energization of relays 275 and 252. Armature 279 of relay 275 closes the circuit for relay 280 from live pole of grounded battery through the winding of relay 280, front contact and armature 279 of relay 275 to ground. Relay 280 is thus energized and attracts both armatures. The attraction of armature 281 closes the locking circuit through the winding 226 of electromagnet 206 from the live pole of grounded battery through 226, lead 228, contact and switch spring 229, conductor 230, armature 281 and contact to ground. As the electromagnet 206 is sluggish, this holding circuit will be established before said electromagnet will 115 120 125

release. The attraction of the armature 281 also puts ground potential on the multiple test terminals 232 so that the calling subscriber's line will test busy. This circuit 5 extends from test terminals 232 through contact and switch spring 229, conductor 230, armature 281 and contact to ground. The attraction of the armature 282 of relay 280 closed a circuit through the vertical 10 magnet 283 and the private magnet relay 284 as follows: from the live side of the grounded battery 285, side switch wiper 286, contact 287, winding of vertical magnet 283 and relay 284, front contact and armature 15 282, resistance 288 to ground. The vertical magnet and the private magnet relay are prevented from operating by the resistance 288 in their circuit.

The relay 252 at the repeater attracted its 20 armatures 256 and 257. The attraction of armature 257 closed a circuit for the slow acting relay 258 from the live pole of grounded battery through relay 258, front contact and armature 257 to ground. Relay 258 is thus energized and attracts its 25 armatures 259 and 260. The attraction of the armature 259 extended the circuit of the relay 261 through said armature 259 and front contact to the back contact of armature 257 of relay 252. The attraction of the 30 armature 256 of relay 252 closed a shunt circuit about the condensers 263 and 264, including the impedance coil 265. The conductors 266 and 267 represent a trunk line as 35 112 (Fig. 1) leading to a first connector 101.

The apparatus and circuits are now in condition for the reception of the first series of selective impulses, which in the case assumed will be 10. Upon each interruption 40 of the circuit at the station E by the controller 202, the energizing circuit for the relays 275 and 252 will be interrupted and their armatures will fall back. We will first consider the effect of this series of 45 impulses on the register selector 107. The retraction of the armature 279 of relay 275 short circuits the resistance 288 and thus causes the energization of the vertical magnet 283 and the private magnet relay 284. As the release magnet relay 280 and the 50 private magnet relay 284 are both made slow acting, they will not release during the brief intervals that they are deprived of current while the series of impulses is being transmitted.

In accordance with the assumption that the substation to be selected was No. 99,532, the first series of impulses would consist of ten interruptions of the circuit at the station, causing the armature of relay 275 to be retracted ten times, resulting in ten energizations of the vertical magnet 283, thus raising the brushes of the register selector to the tenth level. The side switch having 65 wipers 277, 286, 292 and 307 is actuated by

the private magnet 290, which upon energization of the relay 284 became energized by a circuit from battery through the winding of said private magnet, contact and armature 291 of relay 284 to ground. The private magnet, however, does not affect the movement of the side switch wipers upon energization, but is constructed to move all of the wipers of the side switch one step upon deenergization. The circuit of the private magnet is interrupted when the armature of the private magnet relay 284 falls back due to the prolonged inclusion of the resistance 288 in its circuit upon the termination of the first series of impulses. The movement of the side switch wipers 292 and 277 will have no effect at this time. However, the movement of the side switch wiper 286 from contact 287 to its second position or contact 294 will result in the substitution of the rotary magnet 293 for the vertical magnet 283 in the previously traced circuit. These interruptions of the circuit at the substation E^1 will also cause the successive deenergization and 80 energization of the relay 252 of the repeater. With the first interruption the armature 257 will fall back, thus completing a circuit for the slow acting relay 261 from live pole of the grounded battery through 261, contact and armature 259 of relay 258, armature 257 and back contact of relay 252 to ground. Relays 258 and 261 being slow acting will hold up during the series of 90 impulses.

The attraction of the armatures 266 and 267 of relay 261 interrupted the circuit from the sides 266 and 267 of the trunk through the condensers 263 and 264 respectively, and the armature 267 completed a short circuit about the impedance coil 265. Now upon each attraction of the armature 256 of the relay 252, a low resistance bridge will be completed across the trunk conductors 266 and 267, causing the operation 105 of the first selector 101 associated therewith in the usual and obvious manner, stepping the brushes thereof up in unison with the travel of the brushes at the register selector 107. Upon the termination of this 110 series of impulses, the first selector 101 would automatically hunt for an idle second selector 102 in the usual manner.

The apparatus is now in condition for the reception of the second series of impulses, which in the case assumed would be 10. Upon the reception of this series of impulses, the brushes of the register selector 107 will be moved to the tenth set of terminals in the tenth level, which, in the case 125 assumed, is the set individual to the satellite E^1 , and at the termination of the series, the side switch will take another step, placing the wipers in third position. Simultaneously the brushes of the second selector 102, 130

(Fig. 1) will be stepped up to the tenth level and will then hunt for the terminals of an idle third selector in a manner now well understood.

5 In the register selector 107 all the corresponding contacts in all the levels, with the exception of the set individual to the satellite or the tenth set in the tenth level, may be electrically united. The tip and 10 ring contacts may then be electrically connected by a loop conductor 394. It is obvious that such a conductor may be provided for each pair of such contacts or that the corresponding contacts of each level may 15 be tied together and a loop conductor provided for each level. The sleeve contacts, however, with the exception of the tenth contact in the tenth level, are all connected to a conductor 295. The tip, ring and sleeve 20 contacts 302, 303 and 304 respectively, of the tenth level, however, are not united to the other contacts in this level, but instead are joined to conductors 296 and 297 and 298 respectively, leading to a hundreds selector 25 108, one hundreds selector being provided for each register selector. In the call assumed the brushes 299, 300 and 301 of the register selector will now be in engagement with the contacts 302, 303, 304 respectively, 30 and a circuit will be completed for the cut-off relay 270 as follows: from the live pole of the grounded battery through the winding of relay 270, conductor 271, armature and contact of relay 415, conductor 298, contact 304, brush 301, conductor 305, side switch contact 306, wiper 307, armature 272 and back contact, conductor 273, contact and armature 260 of relay 258 to ground. Relay 270 is thereupon energized and a holding circuit is 40 completed therefor through its armature 250 and front contact, contact 215 and spring 216 to ground. This interrupts the circuit for the relays 252 and 275. The relay 275 moreover has its circuit interrupted when the side switch wiper 277 moves to third position. Relays 252 and 45 275 are therefore deenergized. Upon the energization of relay 270 and the deenergization of relay 252, the bridge across the 50 sides 266, 267 of the trunk line of the selectors 101 and 102 is interrupted and these selectors therefore return to normal.

The relay 280 being slow acting does not release as a holding circuit is completed 55 over conductor 295 at the hundreds selector 108. With the brushes 299 and 300 resting on the contacts 302 and 303 respectively, and the side switch in third position, a circuit is completed for the relay 60 416 as follows: from the live pole of grounded battery through upper winding of said relay, conductor 296, contact 302, brush 299, side switch contact 308, wiper 277, conductor 278, armature 255 and front 65 contact, front contact and armature 254, con-

tact and line finder switch spring 207, side 201 of the calling subscriber's line, substitution apparatus at e^1 , side 200 of the line, switch spring 203 and contact, conductor 227, side switch wiper 292, contact 309, 70 brush 300, contact 308, conductor 297 and lower winding of relay 416 to ground. Relay 416 pulls up and completes a circuit for the release magnet relay 417 from live pole of the grounded battery through the winding of said relay, front contact and armature of relay 416 to ground. 75

The attraction of the upper armature of relay 417 placed ground upon the conductor 295, thus completing the circuit for the release 80 magnet relay 280 of the register selector as follows: from live pole of the grounded battery through winding of relay 280, conductor 295, upper armature and contact of relay 417 to ground. The attraction of the 85 lower armature of the relay 417 extended the circuit of the vertical magnet 418 and the private magnet relay 419 to the back contact of relay 416, this circuit being traced from battery through the side switch wiper 90 420 and contact, vertical magnet 418, relay 419, front contact and lower armature of 417 to back contact of relay 416.

The hundreds selector 108 is now in condition to receive the next series of selective 95 impulses. As previously explained, only so much of the hundreds selector and final connector is shown in Fig. 3 as is necessary to illustrate the principal signaling and talking circuits to the called subscriber's 100 station e^2 . When the brushes 299, 300 and 301 of the selector register engaged the contacts 302, 303 and 304 respectively, the relay 416 was energized as just explained and thus prepared the hundreds selector for 105 operation in the well known manner by the impulses which subsequently occurred. In the case assumed, six impulses would now be sent and the brushes of the hundreds selector would be raised to the sixth level 110 when they would automatically hunt for an idle connector 109. The ensuing series of impulses would now cause the brushes of the connector first to be stepped up to the fourth level and then upon the final series, 115 would be stepped around to the third set of contacts in this level, which are the terminals of the called subscriber's line. When the brushes made contact with the terminals of the called subscriber's line, ground was 120 placed on the test conductor 421 through the grounded contact of the lowermost side switch wiper which now connects with contact 410, thus assuring that no other connector would stop on any of the multiple 125 terminals of the called subscriber's line.

Any well known method may be employed for signaling the called subscriber, and upon his response by lifting his receiver from his hook, a complete talking circuit will be es- 130

tablished as follows: from the transmitter at station e^1 side 200 of the line, switch spring 203 and contact, conductor 227, side switch wiper 292, contact 309, brush 300, contact 308, conductor 297, brush 401 and its contact, conductor 423, condenser 405, brush and contact 403, side 200' of the called subscriber's line, telephone apparatus of the called subscriber, side 201' of the line, contact 402 and brush, condenser 404, conductor 422, contact 400 and brush, conductor 296, contact 302, brush 299, contact 308, side switch wiper 277, conductor 278, armature 255 and front contact, front contact and armature 254, contact and switch spring 207, side 201 of the line, back to the telephone apparatus at e^1 .

The talking current will be supplied to the calling subscriber's station from battery 408 through the windings of the relay 406 and to the called subscriber's station from battery 408 through the windings of relay 407, the talking circuit being interrupted to battery between the connections of these relays to the sides of the line by condensers 404 and 405.

Upon the termination of the conversation when the calling subscriber replaces his receiver upon the hook, the circuit for the relays 416 and 406 will be interrupted and the hundreds selector 108 and the final connector 109 will then be returned to normal in the usual manner. The deenergization of the relay 417 of the hundreds selector 108 will remove ground from the conductor 295, thus interrupting the circuit for the release magnet relay 280 of the register selector. Upon the retraction of the armature 282 of relay 280, the circuit for the release magnet 312 will be completed from the live pole of grounded battery through winding of relay 312, off-normal contact 313, back contact and armature 282, back contact and armature 279 to ground, thus energizing the release magnet 312 and returning the register selector to normal. The retraction of the armature 281 of relay 280 will interrupt the circuit for the coil 226 of the electromagnet 206 and the trunk finder 105 will return to normal, thus interrupting at spring 216 the holding circuit for the cut-off relay 270 and allowing its armatures to be retracted. All the switching apparatus will now have assumed its normal position.

We will now assume a call which is not local to the satellite E^1 and consequently one in which the called subscriber's number is not in the ninety ninth thousand, and we will further assume that the wanted subscriber's number is 78,631. Again upon sending the first series of impulses, which in this case would now be eight, the brushes of the register selector 107 at the satellite and of the first selector 101 at the main office E would be stepped up in unison as

before described, and as before the hundreds selector 101, upon the termination of this series of impulses, would select an idle selector 102 and the side switch wipers of the register selector 107 would move to second position, substituting the rotary magnet for the vertical magnet. Now upon sending the second series of impulses or in the present case nine, the brushes of the second selector 102 at the main exchange E , and the brushes of the register selector 107 at the satellite would step in unison, the former being raised to the ninth level, while the latter would be directed to the ninth set of contacts in the eighth level. Upon the termination of the second series of impulses, the second selector 102 at the main exchange would automatically hunt for an idle third selector 103.

As previously described, all the corresponding contacts of the register selector 107 in a series of contacts or level, with the exception of the tenth set in the tenth level, are electrically united, the tip and ring contacts being connected by a conductor as 394, 90 while the sleeve contacts are joined to a conductor 295. The brushes 299, 300 and 301, will now rest, for example, in engagement with the contacts 314, 315 and 316 respectively. A circuit will now be completed for the private magnet relay 280 from the live pole of the grounded battery through the winding of said relay, conductor 295, contact 316, brush 301, conductor 305, side switch contact 306, wiper 307 (the side switch being now in third position), armature 272 and back contact, contact and lower armature 260 of relay 258 to ground, thus holding the release magnet 280 energized and preventing the return to normal of the register selector. When the side switch wiper 277 moved to third position, the original energizing circuit for the relay 252 was interrupted but a substitute path was provided around the interruption as follows: 100 live pole of the grounded battery 251, left winding of relay 252, contact 253, armature 254, contact and brush 207, side 201 of the calling subscriber's line, substation apparatus at e^1 , side 200 of the line, switch spring 203 and contact, conductor 227, side switch wiper 292, contact 309, brush 300, contact 315, loop conductor 394, contact 314, brush 299, contact 308, wiper 277, conductor 278, armature 255 and back contact and right winding of 110 252 to ground. The stepping relay 275 of the register selector having now been removed from connection to the calling subscriber's line and the brushes being connected by the loop conductor 294, 125 the succeeding series of impulses will have no further effect on the satellite apparatus with the exception of the repeater. If now the remaining series of impulses of 7, 4 and 2 respectively, be sent, the brushes of the 130

third selector 103 will be stepped up to the seventh level in which they will automatically seek for an idle final connector such as 104, and the final connector in turn will be actuated to raise its brushes first to the fourth level, and then to rotate the brushes to the second set of contacts in the fourth level or the terminals of the wanted subscriber's line. As this operation would take 10 place in a manner which is obvious and is now well understood, further description thereof is believed to be unnecessary. Had the first series consisted of ten impulses and the second series any number but ten, obviously precisely the same result would have been obtained as all the terminals in the tenth level, with the exception of the final or tenth set, are joined together in the same manner as are the contacts of the other 20 levels.

While in the embodiment of the system herein specifically described the invention is disclosed as applied to a satellite exchange system, it is obvious that the system is adapted, with slight modification, to a broader application as, for illustration, discriminating between groups of subscribers' lines at the same office. It should, therefore, be understood that the invention is to be 30 limited merely by the scope of the appended claims.

We claim:

1. In a telephone exchange system, a main office, a satellite office, interoffice trunk lines 35 from said satellite to said main office, local trunk lines at said satellite, automatic switching mechanism at said main exchange and at said satellite for effecting connection between subscribers, controlling 40 devices associated with the satellite for governing the movement of said switching mechanism, means whereby the first series of selective impulses will effect the simultaneous actuation of switching mechanism at said main exchange and at said satellite, and means operated under the control of a controlling device when manipulated in accordance with the number of the wanted subscriber at said satellite for 45 returning said main office switching mechanism to normal and for effecting a talking connection through the switching mechanism at said satellite.

2. In a telephone system, a main office, a satellite office, a series of automatic switching mechanisms at said main office and at said satellite respectively, whereby the line of a calling subscriber may be extended to other subscribers at the exchange or at said 60 satellite, controlling devices associated with said satellite for governing the operation of said switching mechanisms and means whereby the first series of impulses transmitted from one of said controlling devices 65 will simultaneously effect the operation of

switching mechanism at the main exchange and at the satellite, and means operating when the wanted subscriber is at the satellite for interrupting the controlling circuit to the switching mechanism at the main exchange and for extending the line of the calling subscriber through satellite switching mechanism to the line of the subscriber called. 70

3. In a telephone exchange system, a main office, a satellite office, interoffice trunk lines between said satellite and said main office, local trunk lines at said satellite, means operated upon the initiation of a call at the satellite for associating the calling subscriber's line with an interoffice and a local trunk, automatic switching mechanism at said main office and at said satellite respectively, for effecting connection between subscribers, controlling devices associated with 80 said satellite for governing the movement of said switches, and means operated under the control of a controlling device when manipulated in accordance with the number of a wanted subscriber at the satellite whereby the first series of impulses will effect the simultaneous actuation of switching mechanism at said main exchange and at the satellite, and the successive series will cut off the interoffice trunk and extend the connection through the satellite switching mechanism to the wanted subscriber. 90

4. In a telephone exchange system, a main office, a satellite office, interoffice trunk lines between said satellite and said main office, local trunk lines at said satellite, automatic switching mechanism at said main office and at said satellite for effecting connection between subscribers, said switching mechanism including a register selector at said satellite, 100 controlling devices for governing the movement of said switches, and means operated under the control of a controlling device at the satellite when manipulated in accordance with the number of a wanted subscriber at said satellite, whereby said register selector and switching mechanism at said main exchange will be simultaneously actuated by the first series of impulses, and whereby the successive series of impulses will cause the 110 register selector to alter an electrical circuit, and a relay in said circuit for effecting the release of said main office mechanism. 115

5. In a telephone exchange system a main office, a satellite office, interoffice trunk lines 120 between said satellite and said main office, local trunk lines at said satellite, automatic switching mechanism at said exchange and at said satellite respectively for effecting connection between subscribers, controlling 125 devices at said satellite substations for governing the movement of said switches, a cut-off relay, and means operated under the control of a controlling device when manipulated in accordance with the number of a 130

- wanted subscriber at the satellite, whereby switching mechanism at said main exchange and at the satellite will be simultaneously actuated by the first series of impulses and 5 the successive series will effect the energization of said cut-off relay to interrupt the connection to the main office switching mechanism and extend the connection through the satellite switching mechanism 10 to the wanted subscriber.
6. In a telephone exchange system, a main office, a satellite office, interoffice trunks from said satellite to said main office, local trunks at said satellite, automatic switching mechanism for effecting connection 15 between subscribers, said switching mechanism including a register selector at said satellite, controlling devices associated with said satellite for governing the movement of said switches, means at said satellite for associating the line of a calling subscriber thereat with an interoffice trunk and a local trunk upon initiating a call whereby switching mechanism at the main office and at the 20 satellite will be simultaneously actuated by the first series of impulses, a cut-off relay, said register selector being operated under the control of a controlling device when manipulated in accordance with the number 25 of a wanted subscriber at the satellite to complete a circuit for said cut-off relay, whereby the interoffice trunk line will be interrupted and the connection will be completed through local switching mechanism.
- 30 7. In a telephone exchange system, a main office, a satellite office, interoffice trunk lines from said satellite to said main office, local trunks at said satellite, automatic switching mechanism at said main exchange and at 35 said satellite for effecting connection between subscribers, controlling devices at said satellite substations for governing the movement of said switches, cut-off relays for interrupting said interoffice trunks, and 40 means operated under the control of a controlling device when manipulated in accordance with the number of a wanted subscriber at the satellite, whereby the simultaneous actuation of switching mechanism at 45 50 said main exchange and at said satellite will be effected by the first series of impulses, and whereby the successive series will cause the energization of one of said cut-off relays and complete the connection through 55 the satellite switching mechanism only when the wanted subscriber is at the satellite.
8. In a telephone system, subscribers' lines, automatic switches for interconnecting said lines, one group of said switches 60 being provided to extend a connection to lines of a certain group only, and other switches arranged to extend a calling line to other subscribers' lines, controlling devices for governing the operation of said switches, 65 and means whereby the first series of im-

pulses transmitted from one of said controlling devices will simultaneously actuate a switch in said group and one of said other switches, and means operating when the calling and called lines are in the same group 70 for completing the connection through that switch individual to said group and for interrupting the controlling circuit to the other switching mechanism.

9. In a telephone system, groups of subscribers' lines, automatic switches for interconnecting said lines, one group of said switches being provided to extend the connection to lines of a certain group and another group of said switches arranged to 80 extend a calling line to other subscribers' lines, controlling devices for governing the operation of said switches, and means operating under the control of a controlling device when manipulated in accordance with 85 the number of a wanted subscriber, whereby the first series of controlling impulses will simultaneously actuate a switch in each of said groups, and whereby the succeeding series of impulses will extend the connection 90 through only that one of said simultaneously operated switches which has access to the group of the called subscriber.

10. In a telephone exchange a group of subscribers' lines, other subscribers' lines, 95 automatic switches for interconnecting said lines, a group of switches for extending a connection to lines of said group only and other switches arranged to extend a connection to other subscribers' lines, controlling 100 devices for governing the operation of said switches, and means operating under the control of a controlling device when manipulated in accordance with the number of a wanted subscriber, whereby the first series of 105 controlling impulses transmitted will simultaneously actuate a switch in said group and one of said other switches, and whereby the succeeding series of impulses will extend the connection through one or the other of said 110 simultaneously actuated switches according to whether the called subscriber is located in the same group with the calling subscriber or is external thereto.

11. In a telephone system, subscribers' 115 lines, a plurality of groups of switches for interconnecting said lines, said groups being arranged to extend a connection to different groups of subscribers, controlling devices for governing the operation of said switches, 120 and means actuated upon the operation of one of said controlling devices for first simultaneously actuating a switch in each group and for subsequently releasing all but that one of said switches which has access to 125 the line of the called subscriber.

12. In a telephone system, subscribers' lines, a plurality of groups of switches for interconnecting said lines, the switches of said groups being arranged to extend a con- 130

nection to different groups of subscribers' lines, controlling devices for governing the operation of said switches, and means actuated when one of said controlling devices is operated in accordance with the number of a wanted subscriber for first simultaneously actuating a switch in each group and for subsequently extending the connection through one of said switches to the line of

the wanted subscriber and for releasing the other switches.

In witness whereof, we hereunto subscribe our names this 7th day of May A. D., 1913.

FRANK N. REEVES.
ALBEN E. LUNDELL.
